UNITED STATES PATENT OFFICE.

CHARLES O. JACKSON, OF FAIRMONT, WEST VIRGINIA.

HEADLIGHT-STEERING MECHANISM.

1,121,587.

Specification of Letters Patent. Patented Dec. 15, 1914.

Application filed March 18, 1914. Serial No. 825,521.

To all whom it may concern:

Be it known that I, CHARLES O. JACKSON, a citizen of the United States of America, and resident of Fairmont, county of Marion, 5 and State of West Virginia, have invented certain new and useful Improvements in Headlight-Steering Mechanism, of which the following is a specification.

This invention relates broadly to dirigible headlights, and more particularly to steering mechanism for the headlights of motor vehicles.

The primary object of the invention is to provide a headlight steering mechanism which is extremely simple and inexpensive in construction and which shall at all times act to cause said headlights to direct the light in the direction taken by the front wheels of the vehicle.

A further object is to provide mechanism of the character mentioned which is readily applicable to any of the various present styles or types of automobiles with but little, if any, change in the form of its parts.

With these and other objects in view, the invention resides in the features of construction, arrangement of parts and combinations of elements which will hereinafter be fully described, reference being had to the accompanying drawings, forming a part of this specification, in which—

Figure 1 is a top plan view of the invention applied; Fig. 2 is a front elevation of the same; Fig. 3 is a detail perspective view of the invention; and Fig. 4 is an enlarged horizontal section on the line 4—4, Fig. 2.

Referring to said drawings, in which like designating characters distinguish like parts throughout the several views—1 indicates the front axle, 2 the steering knuckle, 3 the projecting steering arm carried by said knuckle, 4 the stub axle, 5 the tie rod, and 6 the front end portion of a frame sill, all of a common or well known construction.

Mounted at a suitable point, as on the steering arm 3 or other projecting part which is movable with the steering knuckle, is a suitable clamp, as 7, on which is disposed an upright stationary post 8. To the upper end of said post is pivotally connected one end of a horizontally disposed rod or pitman 9 which has its opposite end pivotally connected to the outer end of a horizontally disposed lever 10 which normally stands at substantially a right angle

to said pitman. The opposite end of said lever is rigidly connected to the lower end of a vertical standard 11 which is mounted, and has rotary movement, in a suitable bearing 12 carried at a convenient point, as on the side of the frame sill 6. Mounted upon or formed integral with the standard 11 is the supporting arm or pedestal 13 for a headlight 14.

As is obvious, the turning of the steering knuckle 2 effects the shifting of the position of the steering arm 3 with respect to the frame sill 6, and, through the intermediate post 8 and pitman 9, produces a corresponding shifting movement of the lever 10, thus causing the standard 11 to rotate in its bearing 12, carrying the lamp 14 therewith and causing the light rays to be directed forward in the direction taken by the front 75 wheels due to the said turning of the steering knuckle. Knobs or balls 15 and 16 are provided on the upper end of the post 8 and on the outer end of the lever 10, respectively, the same being seated within slotted members or yokes 17 and 18 which are adjustably mounted on the opposite ends of said pitman, said balls and members constituting ball-joints. The members 17 and 18 are disposed so that the slots thereof occupy 80 planes at right angles to each other, a flexible construction of substantially universal joint type being thus afforded which permits of the application of the clamp 7 in practically any desired position, with respect to 85 the lever 10 without changing the operative relation of said parts.

What is claimed is—

1. The combination with the front-running gear of a motor vehicle, of a bearing mounted 95 upon the frame sill at a suitable point, a standard rotatably mounted in said bearing and carrying a headlight thereon, a horizontally disposed lever having one end rigidly attached to said standard, an upright post mounted upon the steering arm 100 of said running gear, and a pitman disposed horizontally between said lever and the upper end of said post and having ball-joint connection at its ends with said lever and said post, said pitman having adjustable ball-receiving yokes on its opposite ends and said yokes having the openings thereof disposed in planes at right angles to each other.

2. Headlight steering mechanism comprising, in combination with the steering

arm of a motor vehicle, a clamp removably mounted on said arm, an upright post carried by said clamp, a horizontally disposed pitman having ball-joint connection at one end with the upper end of said post, a lever disposed at substantial right angles to said pitman and having ball-joint connection at one end with the opposite end of the latter, said pitman having adjustable ball-receiving yokes on its opposite ends and said yokes having the openings thereof disposed in

planes at right angles to each other, a bearing, an upright standard rotatably mounted in said bearing and rigidly connected to the opposite end of said lever, and a lamp mounted in fixed relation to said standard.

In testimony whereof, I affix my signature in presence of two subscribing witnesses.

CHARLES O. JACKSON.
